UNITED STATES PATENT OFFICE.

RICHARD YOUNG, OF BROOKLYN, NEW YORK.

COMBINED CREASING AND EMBOSSED TOOL.

SPECIFICATION forming part of Letters Patent No. 224,759, dated February 17, 1880.

Application filed September 15, 1879.

To all whom it may concern:

Be it known that I, RICHARD YOUNG, of Brooklyn, in the county of Kings and State of New York, have invented a new and Improved 5 Combined Creasing and Embossing Tool, of which the following is a specification.

My invention relates to tools for ornamenting and finishing the surface of leather; and it consists in a tool combining a creaser or 10 marker, such as is used for lining, and a roller for embossing and printing, the creaser being stationary, while the roller is fitted to revolve, so that in use a line or crease and a printed 15 impression are produced at the same time. The tool is used in connection with a drum, hand-jigger, or other machine of usual character for finishing leather.

The improved tool is shown in the accompanying drawings, wherein Figure 1 is a side elevation of the tool, and Fig. 2 a longitudinal section on line $\alpha\alpha$ of Fig. 1.

Similar letters of reference indicate corresponding parts.

A is a plate constituting the shank of the 25 tool, and adapted for attachment in the tool-head of the machine. Near the outer end of shank A a projecting rib, a, is formed at one side, to which a plate, b, is attached by screws b', or by any other suitable means, the end of 30 plate b extending in line with the end of A, so as to form a mortise or recess in which the roller c is attached.

The roller c is sustained upon a pin or stud, d, projecting from plate b, so that one side of 35 the roller projects beyond the mortise and the

roller fits closely in the mortise, so that it can have no sidewise movement on the pin d.

The creaser or liner e is attached rigidly in a slot or mortise that is made for it in the end of shank A adjacent to roller c, and extends 40 the full width of the shank, its ends being rounded, as shown. The outer or marking edge of e is flush with the periphery of roller c, so that they both will bear upon the surface to be 45 ornamented.

In use, the tool being pressed upon the leather and moved in the direction for rotating roller c, the creaser e will form a straight line or crease, while at the same time the roller c will emboss the surface, in a line parallel to 50 the crease, with the pattern that is upon the periphery of the roller. The leather or tool being fed sidewise a suitable distance between each movement of the tool, a series of alternate embossed and creased lines will be formed, giving 55 a highly-ornamental finish to the leather.

To change the roller c for one of a different pattern, screws b are to be taken out, which permits removal of plate b with the roller.

Having thus described my invention, I claim 60 as new and desire to secure by Letters Patent—

The embossing-roller c and rigid creaser e, combined together in the shank A, substantially as and for the purposes set forth. 65

RICHARD YOUNG.
